UNITED STATES PATENT OFFICE

ROSARIO GIGUERE, OF SPRINGFIELD, MASSACHUSETTS, ASSIGNOR OF ONE-HALF TO
JOHN HENRY WILSON, OF HARTFORD, CONNECTICUT

BLUING DEVICE

Application filed October 23, 1930. Serial No. 490,770.

This invention relates to improvements in bluing devices and comprises a figure article adapted to hold bluing material internally or externally in the form of paste or powder wherein the figure article may be immersed in liquid for coloring the same without necessitating the user's hands coming into contact with the bluing material.

The invention further comprises a novel tray or support over which the figure article is adapted to be suspended while not being used and the figure article may be hinged to the tray or receptacle support in such a manner that the tray or receptacle support may form a handle for the figure article while the same is being used or immersed in liquid to be treated.

The primary object of this invention is to provide a device of the above mentioned character including a figure article adapted to contain bluing material within or without the same in any desired form suspended in a hinged fashion over a tray or receptacle whereby the tray or receptacle may function as a handle while the device is being used and may also provide a support and drip catcher while the device is stored after use.

A still further object of this invention, is to provide a device of the above mentioned character including a figure article adapted to contain or confine a quantity of bluing material in order that the device may be used as a toy after the bluing material or contents in the figure article has been exhausted.

A still further object of the invention, is to provide a device of the above mentioned character having comparatively few parts to become out of order and which is adapted to be easily and cheaply manufactured in order to market the device at a minimum charge.

Other objects and advantages of the invention, will become apparent during the course of the following description, forming a part of this specification and in which,

Figure 1 is a side elevation of a preferred embodiment of the invention, illustrating the parts in their assembled position and show-

ing the drip catching tray partially broken away;

Figure 2 is a top elevational view of the same illustrating the manner of supporting the figure article above the drip tray and showing the handle for manipulating the device;

Figure 3 is a side elevation of a modified form of the invention, illustrating the figure article in the form of a mannikin suspended from a supporting member over a drip tray;

Figure 4 is also a modified form of the invention, illustrating the figure article suspended from a twisted wire support associated with a receptacle;

Figure 5 is a further modified form of the invention showing the figure article in the form of a mannikin received on a twisted wire handle having its lower end secured to a receptacle or tray;

Figure 6 is a further modified form of the invention showing a construction similar to Figure 4 in which the figure article is suspended from a twisted wire support in a pivotal fashion;

Figure 7 is a rear elevational view of the same showing the manner in which the twisted wire support is secured to the receptacle;

Figure 8 is a side elevation of a still further modified form of the invention showing a twisted wire support for the figure article pivotally associated with the drip catching receptacle or tray;

Figure 9 is a top elevation of the same illustrating the pivotal connection between the twisted wire support and the tray;

Figure 10 is a diagrammatic view illustrating the manner of using the device as embodied in the invention;

Figure 11 is a side elevation of another modified form of the invention showing a sconce supporting the figure article;

Figure 12 is a front elevation of the same showing the configuration of the sconce and the pivotal arrangement between the support thereof and the figure article;

Figure 13 is a vertical front elevation of a still further modified form of the invention showing the handle attached directly

to a mannikin embracing the bluing material;

Figure 14 is a bottom elevation of one of the figure articles showing a star-shaped member secured thereto by being embedded in the material in which the device is formed; and

Figure 15 is a vertical cross-sectional view of one of the figure articles showing the bluing material received within a central opening in the figure article and a passage is provided through the bluing material for allowing the passage of water therethrough and the circulation therein.

15 In the drawings, wherein for the purpose of illustrating the invention and wherein like reference characters will be employed to designate like parts throughout the same, attention is directed to Figures 1, 2 and 4 to 10 inclusive, wherein the reference character 5 will be generally employed to designate a dish-shaped receptacle preferably cylindrical, having a flat bottom whereby the same may be supported thereon when the device is not in use or is being stored. The receptacle 5 as illustrated in Figures 1, 2, 4, 6 to 10 inclusive are provided with a rolled upper edge 6 adapted to house and confine a piece of wire.

30 The form of the invention illustrated in Figures 1, 2, 8, 9 and 10 includes a piece of wire 7 passed around the receptacle and within the beads 6 and having the free ends thereof as at 8 and 9 twisted to form a shank portion for receiving a suitable handle 9 which may be formed of wood or other material. One of the twisted end portions 8 and 9 may be bent as at 10 to form a hook or supporting member while the free ends thereof may be passed back into the handle 9 by means of a curved section 11. The wire member 7 extends through an opening at a point opposite from the handle to be formed into angular portions 12 terminating in a cross piece 13.

45 The form of the device as illustrated in Figures 1 and 2 includes a figure article which may be in the form of a top, illustrated by the reference character 14 suspended over the tray or receptacle 5 and supported by wire members 15 having one of their ends as at 16 being embedded within the figure article while the free ends of the wire members 15 are coiled as at 17 and 50 pass around the connecting portion 13 of the angular member 12. The top-shaped figure article 14 may be provided with a central opening 18 adapted to receive bluing material 19 in the form of a paste or plastic and the bluing material may be centrally bored as at 20 in order to allow free circulation of water therethrough for accomplishing a quick dissolving action. If desired, the figure article 14 may be provided with a star-shaped member 21 which

has prongs 22, the alternate sides being embedded in the lower portion of the figure article 14 at the mouth of the central opening therein. The figure article 14 may be formed of wood, celluloid or metal and the same may be painted on the outside to harmonize with the color effect of the receptacle 5 and the handle 9 to produce an article pleasing to the eye and adapted to harmonize with the many color schemes produced in household articles.

55 The modified form as illustrated in Figures 8, 9 and 10 include a top-shaped figure article 14' formed of wood, metal or celluloid, having an outer coating of bluing material adhering thereto and the top-shaped figure article 14' may be supported by a piece of wire twisted in U-shaped manner as at 23 having one leg thereof as at 24 embedded or received in the top-shaped figure article 14', while the opposite ends or legs 25 are separated as at 26 terminating in loops 27 passing around the connecting portion 13 of the angle wire members 12, whereby the inverted U-shaped member 23 may be 60 hingedly supported by the connecting portion 13 of the encircling wire member 7.

65 In Figures 4, 6 and 7, a wire 29 is received within the beaded edge 6 of the receptacle 5 and the free ends thereof are twisted as at 28 and extend in a vertical fashion to the receptacle 5. The wire loop member 29 extends through a cut-away portion 30 in the bead 6 as more clearly illustrated in Figure 7. In Figure 4, the twisted wire members 28 of the loop portion 29 are formed into a looped portion 31 having an angular section 32 connecting a vertical extending section 33 by means of another angular portion 34. The upper or free end of the vertical portion 33 is bent upon itself as at 35 to form a loop for receiving a similar loop 36 formed on the upper end of a wire or suspending member 37. Mounted on the lower end of the wire or suspending member 37 is a top-shaped figure article 14'' which may be in the form of a top or other figure article coated or covered with bluing material to produce the best results.

70 The receptacle 5 illustrated in Figure 5, may be beaded as at 67 for receiving the free ends 63 of oppositely extending arms 64 formed on the lower end of a twisted wire shank member 66 having a bent portion 67 in the form of a ring to provide a supporting loop for receiving a hook or other supporting member. The intermediate portion of the shank 66 as at 68 is adapted to receive a mannikin 69 having a central opening 70 for containing a quantity of bluing material. The central bore or opening 7 extends centrally and longitudinally through the mannikin 69 in order that water may be circulated therein for dissolving a portion or portions of the bluing material.

until the required tone or color of the water is effected.

- As set forth in Figures 6 and 7, the twisted free ends 28 of the wire loop 29 are continuous as at 38 and are provided with offset angular portions 39 and 40 which terminate in vertical portions 41 and 42 respectively having their free ends looped as at 43 and 44 for receiving the looped end 45 of a suspending wire or device 46 having its lower end embedded or received in a bluing device in the form of a top covered with bluing material 14'', similar to the top-shaped figure article illustrated in Figure 4.
10. The invention is also adapted to include a device as illustrated in Figure 3, wherein the receptacle 5' is provided with a partially extending bead 6' which terminates in a vertical portion 47 formed integral with the receptacle 5' and tapering toward the upper end thereof as at 48 wherein it is provided with a curved section 49 for supporting a suspending device 50, adapted to have its upper end looped as at 51 for being received in an opening in the curved portion 49 while the lower end of the suspending rod 50 is embedded in a figured article 51 in the form of a mannikin. In this form of figured article, the bluing material may be carried by the mannikin by applying a coating of bluing material thereto or the interior of the mannikin 51 may be hollowed to receive a sufficient quantity of bluing material for accomplishing this purpose.

Figures 11 and 12 illustrate a still further modified form of the invention and show another means of carrying out the invention and the reference character 52 will be employed to designate a receptacle somewhat cylindrical having a sconce-like portion 53 extending vertically therefrom and terminating in a curved upper portion 54. The free end of the curved upper portion 54 is bifurcated as at 55 to receive a loop 56 therebetween formed on the upper end of a suspending wire or rod 57, while a pin 58 extends through the bifurcated portion 55 and through the looped portion 56 of the rod 57 to hingedly connect the same thereto. Mounted on the lower end of the suspending rod 57 is a bluing device 14'' of the same contour and configuration as illustrated in Figures 1, 2, 4, 6 to 12 inclusive, 14 and 15, and includes a top-shaped member formed of a suitable material for containing or supporting a quantity of bluing material in the form of paste or powder.

The device may be presented in the form illustrated in Figure 13 wherein the reference character 58 designates a mannikin having a hollow central portion 59 for receiving a quantity of bluing material or the like. The mannikin 58 may be colored to represent the desired figure and a handle formed of

twisted wire 60 may have its free end 61 embedded and received in the head portion of the mannikin 58. Openings communicating with the central opening or chamber 59 may be provided for allowing circulation of water therethrough in order to dissolve the bluing material contained in the chamber.

For a consideration of the operation of the device, attention is directed to Figures 1 and 2, wherein the handle 9 may be grasped by the operator and the top-shaped member 14 may be moved about its pivot point 17 as illustrated in Figure 10 for being immersed in a receptacle R containing the fluid to be blued or treated. By agitating the water in the device, the bluing material contained within the top-shaped article 14 may be dissolved and the liquid in the receptacle R may be colored to the desired tone.

In the forms of the invention illustrated in Figures 3, 4, 6, 7, 8, 9, 11 and 12, the same operation is performed and in each instance, the figure article may be moved about its suspending or pivot point and the receptacle or a portion thereof will be employed as a handle for agitating the top-shaped figure article in the water to be blued. The device illustrated in Figures 5 and 13 with a mannikin is provided, with an opening for receiving the bluing material, the handle may be grasped and the mannikin submerged within the water to be blued and agitated therein to cause the bluing material to be dissolved to a certain extent in order that the water or liquid will be colored to the desired tone. When any of the devices are not in use or while they are being stored, it is quite evident that the receptacle over which the figure articles are suspended form a support for the device and also form a means of catching the drippings therefrom after the figure articles have been immersed in the water to be blued, thereby preventing the bluing material from coming into contact with articles on which the device is supported.

It is to be understood that the figure article 14, 14' and 14'', 51 and 59 may be of any desired shape or configuration and the invention may be carried out by providing figured articles in the form of bipedes or quadropedes to produce a novel result and to produce an article which may be used first as a bluing holder and secondly as a toy or amusement device after the same has been exhausted of its supply of bluing material.

It is also to be understood that the forms of the invention herewith shown and described are to be taken as the preferred examples of the same and that various changes in the shape, size and arrangement of parts may be resorted to without departing from the spirit of the invention or the scope of the subjoined claims.

I claim:—

1. A bluing device of the character described including a holder, bluing material carried by the holder and means to which the holder is pivotally attached for agitating the same within a liquid.
2. A bluing device of the character described comprising a receptacle, a holder mounted above the receptacle, bluing material carried by the holder and means for agitating the holder within the body of liquid, whereby the bluing material will be partially dissolved.
3. A bluing device of the character described comprising a receptacle, a holder mounted above the receptacle, whereby drippings therefrom will be received in the receptacle, and a quantity of the bluing material supported by the holder.
4. A bluing device of the character described comprising a receptacle, a wire member attached to the receptacle, said wire member extending over the receptacle, a holder supported over the receptacle by means of the wire member, a quantity of bluing material supported by the holder and said wire member including means to facilitate agitation of the holder when the same is immersed within a body of liquid.
5. A bluing device of the character described comprising a receptacle, a handle carried by the receptacle, a holder supported over the receptacle, a quantity of bluing material supported within the holder, and said receptacle being adapted to form a support for the holder when the device is being stored.
6. A bluing device of the character described, a receptacle, a handle carried thereby, a holder adapted to be supported over the receptacle when the device is not being used and while the same is being stored and a quantity of bluing material carried by the holder.
7. A bluing device of the character described comprising a receptacle, a handle carried by the receptacle, a holder mounted above the receptacle, and a quantity of bluing material supported by the holder above the receptacle whereby drippings therefrom may be received in the receptacle.
8. A bluing device of the character described comprising a cylindrical receptacle, a handle carried by the receptacle, a holder mounted over the receptacle, and adapted to be supported by a portion of the handle and a quantity of bluing material carried by the holder whereby the holder may be agitated in a body of water for coloring or bluing the same.
9. A bluing device of the character described comprising a cup-shaped receptacle, a bead formed on the upper edge thereof, a wire loop passing through the bead and having its free ends terminating in a handle

shank, a handle secured to the handle shank, a wire member pivotally secured to a portion of the wire loop, within the bead of the receptacle, said wire member being presented over the receptacle, a holder adapted to be supported by the wire member, and a quantity of bluing material supported by the holder.

10. A bluing device of the character described comprising a cup-shaped receptacle, a bead formed on the upper edge thereof, a wire loop passing through the bead and having its free ends twisted to form a handle shank, a handle secured to the twisted ends of the handle shank, an angular portion formed on the loop member, a wire suspending device pivotally secured to the angular portion of the loop, a holder suspended over the cup-shaped receptacle by means of the suspending device, and a quantity of bluing material contained within the holder.

In testimony whereof I affix my signature.

ROSARIO GIGUERE.
